2016 and grown in a greenhouse in Stuttgart, Germany. The colors shown are as true as can be reasonably obtained by conventional photographic procedures. The photograph is a whole plant photo of 'KLEDP22470' and shows the foliage, 5 buds, and flowers.

DESCRIPTION

The following detailed descriptions set forth the distinctive characteristics of 'KLEDP22470'. The data which define these characteristics were collected from asexual 10 reproductions carried out in Stuttgart, Germany. Data was collected in November 2021 on plants 23-weeks after potting and grown in a plastic greenhouse. Color references are to The R.H.S. Colour Chart of The Royal Horticultural Society of London (R.H.S.), 5th edition (2007).
Classification:

Family.—Caryophyllaceae.

Botanical.—*Dianthus caryophyllus*.

Designation.—'KLEDP22470'.

Parentage.—Mutation parent 'KLEDP07089' (Unpatented).
Plant:

Propagation type.—Vegetative cuttings.

Time to produce a rooted young plant.—4 weeks.

Root description.—Fine and white, RHS 155A.

Rooting habit shape.—Lanceolate.

Plant form.—Upright and mounding.

Plant height.—13 cm.

Plant diameter or spread.—17 cm.

SUMMARY

The following are the most outstanding and distinguishing characteristics of 'KLEDP22470' when grown under normal horticultural practices in Stuttgart, Germany.

1. Double pink and darker pink flowers; and
2. A mounding and upright habit.

DESCRIPTION OF THE PHOTOGRAPH

This new *Dianthus* plant is illustrated by the accompanying photograph of a 12-week-old plant taken in March

<i>Cold/heat tolerance.</i> —The instant plant is cold tolerant but not winter-hardy and is partly heat tolerant.	
<i>Lateral branches/stems:</i>	
<i>Shape of the branch in cross-section.</i> —Circular.	
<i>Number of lateral branches with flower buds or second sets of flower buds.</i> —Few.	5
<i>Hollowness of the branch.</i> —Absent.	
<i>Length.</i> —13 cm.	
<i>Diameter.</i> —0.2 cm.	
<i>Internode length.</i> —1.7 cm.	10
<i>Internode quantity per branch.</i> —5 to 8.	
<i>Node length.</i> —0.3 cm.	
<i>Node diameter.</i> —0.3 cm.	
<i>Texture.</i> —Smooth.	15
<i>Color.</i> —RHS 145C (Yellow-Green).	
<i>Flower clustering on the lateral branch.</i> —In some lateral branches.	
<i>Foliage:</i>	
<i>Arrangement.</i> —Opposite.	20
<i>Length.</i> —5.0 cm.	
<i>Width.</i> —0.4 cm.	
<i>Shape.</i> —Obovate.	
<i>Apex.</i> —Acute.	
<i>Base.</i> —Obtuse.	
<i>Margin.</i> —Entire.	
<i>Texture (both upper and lower surfaces).</i> —Smooth.	
<i>Cross-section of the leaf.</i> —Moderately concave.	
<i>Curvature of the leaf.</i> —Absent.	
<i>Glaucosity of the leaf.</i> —Weak.	30
<i>Leaf color (both immature and mature).</i> —Upper surface: RHS 143B (Green) for immature and RHS N137A (Green) for mature. Lower surface: RHS 143B (Green) for immature and RHS 137A (Green) for mature.	
<i>Venation pattern.</i> —Parallel.	35
<i>Venation color (for both upper and lower surfaces).</i> —RHS 137A (Green).	
<i>Flowers:</i>	
<i>Flower type and habit.</i> —Double, small sprays, round; 2 to 4 flowers per spray.	40
<i>Fragrance.</i> —Present; sweet and slight.	
<i>Position of the flowers compared to the foliage of the plant.</i> —Same level.	
<i>Profile of both the upper and lower part in the lateral view.</i> —Flat convex.	45
<i>Natural flowering season.</i> —Spring to Fall.	
<i>Flower longevity on the plant.</i> —10 to 15 days.	
<i>Inflorescence shape.</i> —Slightly domed.	
<i>Buds:</i>	
<i>Length.</i> —1.9 cm.	
<i>Diameter.</i> —0.6 cm.	
<i>Shape.</i> —Elliptic.	
<i>Color.</i> —RHS 143A (Green) to RHS 145B (Yellow-Green).	
<i>Extrusion of the styles at the bud stage.</i> —Absent.	
<i>Corolla:</i>	
<i>Quantity of petals and arrangement.</i> —16 and arranged in several whorls.	
<i>Corolla height.</i> —1.0 cm.	
<i>Petal length.</i> —1.9 cm.	60
<i>Petal width.</i> —1.3 cm.	
<i>Petal shape.</i> —Obtuse.	
<i>Petal apex.</i> —Obtuse.	
<i>Petal base.</i> —Acute.	
<i>Petal margin.</i> —Crenate.	65
<i>Depth of petal margin.</i> —Shallow.	
<i>Petal texture (both upper and lower surfaces).</i> —Smooth.	
<i>Petal color (immature).</i> —Upper surface: RHS 60D (Red-Purple) and RHS 60B (Red-Purple). Lower surface: RHS N66C (Red-Purple).	
<i>Petal color (mature).</i> —Upper surface: RHS 61C (Red-Purple) and RHS 61B (Red-Purple). Lower surface: RHS N66C (Red-Purple). Other markings: No stripes, speckles, area of flush, or macules.	
<i>Calyx.</i> —Quantity of sepals and arrangement: Composed of 5 sepals. Longitudinal axis of the lobes of the calyx: Straight. Shape: Cylindrical. Calyx height: 1.7 cm. Calyx diameter (at the apex): 1.8 cm. Sepal texture (both upper and lower surfaces): Smooth. Sepal color: Upper surface: RHS 143A (Yellow-Green). Lower surface: RHS 145B (Yellow-Green). Anthocyanin coloration: Absent. Position of the outer lobes of the epicalyx in relation to the calyx: Adpressed. Apex shape of the outer lobes of the epicalyx: Acute. Apex shape of the inner lobes of the epicalyx: Short acuminate.	
<i>Peduncles:</i>	
<i>Length.</i> —0.6 cm.	
<i>Diameter.</i> —0.2 cm.	
<i>Strength.</i> —Strong.	
<i>Texture.</i> —Smooth.	
<i>Color.</i> —RHS 145A (Yellow-Green).	
<i>Reproductive organs:</i>	
<i>Stamens.</i> —Quantity per flower: 8. Filament length: 0.6 cm. Filament color: RHS NN155C (White). Anther length: 0.5 cm. Anther diameter: Less than 0.1 cm. Anther color: RHS 163C (Greyed-Orange). Pollen amount: None observed.	
<i>Pistils.</i> —Quantity per flower: 2. Length: 1.0 cm. Diameter: Less than 0.1 cm. Stigma: Color: RHS NN155C (White). Shape: Filamentous. Length: 0.2 cm. Diameter: Less than 0.1 cm. Style: Color: RHS NN155C (White). Length: 0.1 cm. Diameter: Less than 0.1 cm. Shoulder: Absent. Ovary: Color: RHS 145C (Yellow-Green). Shape: Oblong. Length: 1.0 cm. Surface texture: Smooth.	
<i>Fruit and seed set:</i> Sometimes observed but no information is available.	
<i>Disease and pest/insect resistance:</i> No disease and pest/insect resistance observed.

COMPARISON OF 'KLEDP22470' WITH PARENTAL LINE AND KNOWN VARIETY

'KLEDP22470' is distinguished from the mutation parent as described in Table 1.

TABLE 1

Comparison with Parental Line		
Characteristic	'KLEDP22470'	Mutation Parent 'KLEDP07089'
Flower color, general	Pink and darker pink	Pink with purple centers

‘KLEDP22470’ can be compared to the commercial *Dianthus* variety ‘KLEDP07088’ (Unpatented). Differences between the varieties are described in Table 2.

TABLE 2

Comparison with Similar Variety		
Characteristic	‘KLEDP22470’	‘KLEDP07088’
Flower color, general	Pink and darker pink	Pink with Red-Purple and white pattern

TABLE 2-continued

Comparison with Similar Variety		
Characteristic	‘KLEDP22470’	‘KLEDP07088’
Growth Habit	Compact Upright and mounding	Medium Semi-upright

I claim:

1. A new and distinct variety of *Dianthus* plant designated ‘KLEDP22470’ as illustrated and described herein.
